(57) **CLAIM**

The ornamental design for a watering can, as shown and described.

DESCRIPTION

FIG. 1 is a front, right and top perspective view of a watering can, showing my new design;

FIG. 2 is a rear, left and bottom perspective view thereof;

FIG. 3 is a front view thereof;

FIG. 4 is a rear view thereof;

FIG. 5 is an enlarged left side view thereof;

FIG. 6 is an enlarged right side view thereof;

FIG. 7 is a top plan view thereof;

FIG. 8 is a bottom plan view thereof; and,

FIG. 9 is an enlarged view of portion of FIG. 1 thereof. The broken lines shown in the drawings illustrate portions of the watering can that form no part of the claimed design.

1 Claim, 9 Drawing Sheets
